UNITED STATES PATENT OFFICE.

ISAAC E. SEXTON, OF WINCHESTER, MASSACHUSETTS.

CAN NOZZLE.

Application filed July 9, 1925. Serial No. 42,456.

To all whom it may concern:

Be it known that I, ISAAC E. SEXTON, a citizen of the United States, residing at Winchester, in the county of Middlesex and State of Massachusetts, have invented new and useful Improvements in Can Nozzles, of which the following is a specification.

This invention relates to a sheet metal can, and particularly to a pouring nozzle therefor adapted to cooperate with a closing cap to form a liquid-tight closure, the cap including a top portion having a compressible packing layer on its inner side, and an annular flange embracing the nozzle and provided with lugs constituting an element of means for pressing the packing layer against the nozzle mouth, the nozzle being provided with pressing means adapted to cooperate with said lugs.

The object of the invention is to provide a sheet metal nozzle of improved construction including a packing layer seat which is extremely rigid and free from liability of deformation by sealing pressure exerted upon it, and adapted to cooperate with the packing layer in forming a continuous liquid-tight joint, and means permitting a limited rotation of the cap in one direction only, and so limiting said rotation as to prevent the possibility of the unintentional release of the cap from the neck.

Of the accompanying drawings forming a part of this specification,—

Figure 1 is a side view of a cam nozzle embodying the invention.

Figure 2 is an end view of the same, a portion being shown in section.

Figure 3 is a section on line 3—3 of Figure 2.

Figure 4 is an end view of the partly completed blank from which the nozzle is made.

Figure 5 is a section on line 5—5 of Figure 4.

Figure 6 is a side view of the cap.

Figure 7 is a section on line 7—7 of Figure 6.

Figure 8 is a view similar to Figure 3, showing the cap engaged with the nozzle.

Figure 9 is a fragmentary sectional view, showing a portion of the nozzle on line 9—9 of Figure 2, and the portion of the cap which includes one of the lugs.

The drawing shows the nozzle and cap considerably enlarged.

The same reference characters indicate the same parts in all of the figures.

The cap which cooperates with my improved nozzle includes a top 12, having on its inner side a compressible packing layer 13, and an annular flange 14, formed to surround the nozzle and provided with inwardly projecting lugs 15, which, in this instance, are bosses pressed inward from the flange.

The nozzle comprises a preferably seamless tubular sheet metal body 16, formed at its inner end for attachment to the top 17 (Figure 3) of a sheet metal can, said top having an aperture surrounded by the body 16. As here shown, the margin of the aperture is formed by a narrow upwardly projecting flange 18, entering the lower end of the body 17 and soldered to the latter.

The outer end of the body 16 is rolled or turned outward, to form an annular neck constituting a continuous annular seat 19, for the packing layer 13, said seat being rounded in cross section, and adapted to cooperate with the packing layer in forming a liquid-tight joint. From the neck or seat 19 depends a continuous flange 20, surrounding the body 16, and spaced by the seat from the body.

The seat and flange are integral with the body, and the flange reinforces and stiffens the seat and prevents deformation of the latter by pressure exerted on it by the cap.

Extending across the flange are transverse indentations constituting guides 21, through which the cap lugs 15 are movable. Each guide has a shorter end 22, and a longer end 23 (Figure 1). The indentations serve to stiffen the flange 20, by imparting a partially corrugated form thereto. The lower edge of the flange 20 is diversified, and includes cam-shaped edge portions 24, inclined downward from the shorter ends 22 of the guides, stops 25, projecting downward from the lower ends of the portions 24, and inclined portions 26 (Figure 1) at the lower ends of the indentations forming the guides.

The cap lugs 15 are arranged to simultaneously enter the guides. When the packing layer comes to a bearing on the seat 19, the lugs 15 are in the position shown by dotted lines at the central portion of Figure 1. A partial forward rotation of the cap in the direction of the arrow α in Figures 1 and 6, is now permitted, said rotation causing the lugs to cooperate with the cam-shaped edge portions 24 in pressing the cap downward, and increasing the pressure of its packing layer on the seat 19.

The stops 25 limit the forward rotation of the cap by arresting the lugs 15 at the lower ends of the cam-shaped edge portions 24, as indicated by dotted lines at the right hand portion of Figure 1. The lugs are therefore prevented from being carried by the forward rotation of the cap beyond the lower ends of the portions 24, and from entering the guides 21, so that provision is made for preventing an unintentional release of the cap by continuing its forward rotation too far.

The cap may be released by rotating it backward until the lugs encounter the longer ends 23 of the guides.

The nozzle may be formed from a flat discoidal blank of sheet metal, by suitable pressing and cutting dies, the blank being in the form shown by Figures 4 and 5, at one stage 20 of the forming operation. At this stage the body 16 has its final form, and is closed at one end by the central portion 30 of the blank, which portion is subsequently cut out to leave the end open. A flat annular incipient flange 31 now projects outward from the outer end of the body 16, the width of this flange being such that the neck or seat 19 and the flange 20 may be formed from it, as indicated by dotted lines in Figure 5, by a 25 subsequent operation involving the bending of the incipient flange to form the seat and the flange 20, and the cutting away of the marginal portion to form the edge portions 24, 25 and 26.

It will be seen that I am enabled, by providing the stops 25, to give the cam-shaped edge portions 24 a relatively slight or gentle inclination, instead of an abrupt inclination, the degrees of inclination being such that a 40 minimum force is sufficient to turn the cap to its sealing position, the stops arresting the forward rotation of the cap when the lugs 15 are out of registration with the guides.

I claim:

1. A can nozzle for use with a flanged closing cap having a packing layer on its top and inwardly projecting lugs on its flange, said nozzle comprising a tubular sheet metal body formed at its inner end for attachment to an apertured can top, and

provided at its outer end with an outwardly turned neck constituting a continuous annular seat for said packing layer, and with a continuous flange depending from the seat, surrounding the body, and spaced by the 55 seat from the body, said flange reinforcing and stiffening the seat against deformation by pressure of the cap against it, and having transverse indentations extending across and stiffening the flange, and constituting guides for the cap lugs, each guide having a shorter and a longer side wall, and cam-shaped lower edge portions inclined downward from the shorter side walls of the guides, and adapted to cooperate with the 60 cap lugs in pressing the packing layer against the seat.

2. A can nozzle for use with a flanged closing cap having a packing layer on its top and inwardly projecting lugs on its flange, 70 said nozzle comprising a tubular sheet metal body formed at its inner end for attachment to an apertured can top, and provided at its outer end with an outwardly turned neck constituting a continuous annular seat for 75 said packing layer, and with a continuous flange depending from the seat, surrounding the body, and spaced by the seat from the body, said flange reinforcing and stiffening the seat against deformation by pressure of the cap against it, and having transverse indentations extending across and stiffening the flange, and constituting guides for the 80 cap lugs, each guide having a shorter and a longer side wall, cam-shaped lower edge 85 portions inclined downward from the shorter side walls of the guides, and adapted to cooperate with the cap lugs in pressing the packing layer against the seat, and stops 90 projecting downward from the lower ends of the cam-shaped portions, said stops permitting a partial forward rotation of the cap, to cause its lugs to cooperate with the cam-shaped edge portions, and limiting said 95 forward rotation to prevent the lugs from being carried thereby beyond the lower ends of said portions and entering the guides.

In testimony whereof I have affixed my signature.

ISAAC E. SEXTON.
